BUSHING PULLER

Robert P. Kingston, Indianapolis, Ind.

Application February 6, 1939, Serial No. 254,861

3 Claims. (Cl. 29—88.2)

The present application relates to a bushing puller, and the primary object of the invention is to provide a tool of the character described which shall be usable in either applying tight-fitting bushings to their seats, or in removing such bushings from their seats. It is a further object of the invention to provide such a tool which shall be of such character that it will be adaptable to bushings of rather widely-varying diameters; that it may be operated without special skill to remove or place bushings quickly and accurately and without damage to the bushings or to their seats. It is a further object of the invention to provide a tool of the character described through which it shall be possible to apply enormous forces with relatively slight exertion. Further objects of the invention will appear as the description proceeds.

To the accomplishment of the above and related objects, my invention may be embodied in the forms illustrated in the accompanying drawing, attention being called to the fact, however, that the drawing is illustrative only, and that change may be made in the specific construction illustrated and described, so long as the scope of the appended claims is not violated.

Fig. 1 is a longitudinal section through an embodiment of my invention, in assembled condition with certain fittings applied thereto;

Fig. 2 is a side elevation of one form of puller fitting;

Fig. 3 is a longitudinal section, upon an enlarged scale, of another form of puller fitting, a fragment of the stud being shown in association therewith;

Fig. 4 is a side elevation, partly in section, of another form of puller fitting, a fragment of the stud being shown in association therewith;

Fig. 5 is a side elevation, partly in section, of still another form of puller fitting with which is associated a fragment of the puller stud;

Fig. 6 is a side elevation, parts being broken away for clarity of illustration, of a special adapter for use in connection with the tool for a specific application;

Fig. 7 is an isometric view of a fragment of my tool with an auxiliary barrel applied thereto; and

Fig. 8 is an elevation, partly in section, of a puller fitting usable in connection with the organization of Fig. 7.

Referring more particularly to the drawing, it will be seen that I have illustrated a tool comprising a barrel 10, a portion of the outer sur-

face of said barrel preferably being knurled to provide a hand grip. One end 11 of said barrel forms an annular foot, and is adapted to receive any one of a plurality of fittings 12 each of which comprises a cylindrical portion 13 snugly receivable within the end 11 of the barrel 10, and an annular foot surface 14, each fitting 12 being formed with a foot surface 14 of predetermined internal diameter. The end surface 11 of the barrel 10 is preferably formed with two diametrically opposite notches 18 to permit the insertion of a tool for prying the fitting 12 out of its assembled position.

Within the barrel 10 is fixedly received a shell 15 which is formed with a slot 16 therethrough, one end 17 of said slot terminating short of the end of the shell 15 adjacent the foot 11, and the other end 18 of said slot opening through the opposite end of said shell. Slidably mounted within the shell 15 is a sleeve 19 provided with a lateral projection 20 seated within the slot 16.

Said sleeve 19 is formed with an elongated, internally threaded bore 21 receiving the threaded portion 22 of a stem 23 which is journaled in a plug 24. As is clearly to be seen in Fig. 1, the stem 23 is prevented from axial movement with respect to the plug 24 by a shoulder or collar 25 and a nut or head 26 engaging opposite surfaces of said plug 24. Said plug is snugly seated within the end of the barrel 10 opposite the foot 11, and is provided with a flange 27 bearing against said end. The head 26 is preferably formed with a transverse bore 28 to receive an operating hand bolt 29 which is preferably provided, at its opposite ends, with spring pressed balls 30 tending to prevent accidental dislodgment thereof.

It will be obvious that rotation of the stem 23 through the bar 29 will be converted into reciprocation of the sleeve 19; and that enormous forces tending to move said sleeve toward the left, as viewed in Fig. 1, may be applied to said sleeve without excessive exertion, and without applying to the tool any force tending to disassemble said tool.

The sleeve 19 is further formed with a second internally threaded bore 31 receiving the threaded end 32 of a stud 33, one threaded portion 34 of which is projectible beyond the foot 11 or the foot 14. Said projectible portion 34 is adapted to receive any one of a plurality of fittings similar to fitting 35.

It will be seen that the fitting 35 provides a cylindrical surface 36 which is interrupted by a laterally projecting annular shoulder 37 formed

to provide an annular bearing surface 38 substantially perpendicular to the direction of movement of the stud 33. Said fitting is further formed with an internally threaded bore 39 receiving a threaded portion 34 of the stud 33.

In use, the stem 23 is rotated to project the portion 34 of the stud 33. A footpiece 12 of suitable internal diameter is selected and associated with the barrel 10, the diameter of the selected footpiece depending upon the diameter of the bushing to be shifted, it being obvious that the internal diameter of the selected footpiece must be greater, but preferably only slightly greater, than the external diameter of the bushing to be shifted. A fitting similar to the fitting 35 is now selected, the requirements thereof being that the cylindrical surface 36 shall have an external diameter preferably only slightly less than the internal diameter of the bushing to be shifted, and that the shoulder 37 shall be of such external diameter as to make the width of the bearing surface 38 substantially equal to the thickness of the bushing to be shifted.

The fitting 35 is intended primarily for use in applying bushings to their seats. Therefore, the bushing to be applied is sleeved upon the cylindrical surface 36 of the fitting 35, the stud 33 is projected through the bushing seat and thereafter the fitting 35 is threaded on to the portion 34 of the stud 33. The stem 23 is now rotated until the distance between the foot 14 and that end of the bushing adjacent the foot 14 is substantially equal to the length of the bushing seat. The foot 14 is now carefully placed in contact with the adjacent surface of the bushing seat in absolute concentricity with the bushing seat, and the stem 23 is further rotated, thus drawing the fitting 35 and the bushing associated therewith closer to the foot 14, and forcing the bushing to move axially toward its desired position within the bushing seat. Such rotation is continued, thereafter, until the bushing is accurately located within its seat; whereafter the stem 23 is rotated in the opposite direction to back the fitting 35 out of the bushing, leaving the bushing in its seat. When the fitting 35 has so been moved out of the bushing, it may be unthreaded from the stud 33; whereafter the stud 33 may be withdrawn by removing the tool.

The fitting 35' of Fig. 2 is intended primarily for use in removing bushings from their seats; and differs from the fitting 35 only in that its cylindrical surface 36' is shorter than the surface 36. When it is desired to remove a bushing, a suitable footpiece 12 and fitting 35' are selected, the stud 33 is projected through the bushing, the fitting 35' is mounted upon the stud portion 34, the footpiece 12 is placed in absolute concentricity with the external surface of the bushing, and the stem 23 is rotated to draw the cylindrical surface 36' into the bushing. When the shoulder 37' engages the end of the bushing, further rotation of the stem 23 will begin to draw the bushing toward the footpiece 12. In removing a bushing, of course the bushing must be drawn entirely into the barrel 10; and it is for that reason that the end 40 of the shell 15 is spaced from the end 11 of the barrel 10.

After the bushing has been withdrawn from its seat, the tool may be removed; whereafter the fitting 35' is removed from the stem 34 and the bushing, which has been drawn into the barrel 10, may be readily removed therefrom.

In Fig. 3, I have shown a fitting 35'' which

may be alternatively used in place of the fitting 35 or the fitting 35'. The fitting 35'' is provided with an elongated cylindrical surface 41 similar to the surface 36, and with an internally threaded bore 42 similar to the bore 39. Said fitting is further provided with a shorter cylindrical surface 43 similar to the surface 36' and with an internally threaded bore 44 which may be associated with the stud portion 34. The shoulder 45 provides oppositely facing bearing surfaces 46 and 47 corresponding, respectively, with the surfaces 38 and 38'.

Preferably, the fitting 35 is provided with a kerf 48 and the fitting 35' is provided with a kerf 48'. Similarly, the fitting 35'' will be provided at one end with a kerf 49 and at its opposite end with a kerf 50, merely to provide a convenient means for applying reasonable force in applying or removing the fittings from the stem portion 34.

In Fig. 4 I have illustrated a fitting 51 for use in removing bushings which are so located that it is impossible or inconvenient to apply a fitting of the character illustrated in Figs. 1, 2 and 3. For instance, if only one end of the bushing seat is conveniently available, while the other end thereof is so closely adjacent to another element as to make it difficult or impossible to insert a fitting of the character of those illustrated in Figs. 1, 2 and 3 between such bushing seat and such other element, then a fitting, of suitable size, of the character illustrated in Fig. 4 may be applied to stud portion 34. Said fitting 51 comprises a base 52 formed with an internally threaded bore 53 for receiving the stud portion 34, and a plurality of spring fingers 54 arranged to define an annulus 55 of resiliently variable diameter. Each finger 54 is formed with a cammed radial projection 56 terminating in a rearwardly facing, radially extending shoulder 57, the shoulders 57 of all of the fingers 54 cooperating to define an annular bearing surface substantially perpendicular to the line of movement of the stud 33.

When it is desired to remove a bushing of the character above-mentioned, the operator selects a fitting 51 of suitable size, it being obvious that the diameter of the circle defined by the leading edges of the surfaces 56 must be slightly less than the internal diameter of the bushing to be pulled, and that the diameter of the circle defined by the trailing edges of said surfaces 56 must be slightly greater than the internal diameter of the bushing to be pulled.

Applying such fitting 51 to the stud portion 34, and with the stud portion 34 projected beyond the foot 11 or the footpiece 12, the operator manually forces the fitting 51 into the bushing to be pulled. As he does so, the cammed surfaces 56, entering the bushing, will cause the fingers 54 to flex inwardly, thereby reducing the diameters of the circles defined by said surfaces 56, and permitting the leading ends of the fingers 54 to project entirely through the bushing. As said leading ends emerge from the far end of the bushing, the natural resilience of the fingers will cause the same to snap outwardly, whereby the shoulders 57 are projected beyond the internal surface of the bushing and into engagement with the far end of the bushing. The footpiece 12 is now placed in contact with the adjacent surface of the bushing seat; whereafter rotation of the stem 23 in the manner above described will draw the fitting 51 toward the footpiece 12; and the engagement of the bearing sur-

face formed by the shoulders 51 with the far end of the bushing will enforce similar movement of the bushing, whereby the bushing may be withdrawn from its seat.

5 In Fig. 5 I have illustrated a fitting 58 which may be used, in conjunction with my tool, in withdrawing so-called blind bushings, which are so located that even the shouldered ends of the fingers 54 cannot be projected beyond the far 10 end thereof. The fitting 58 comprises a base 59 formed with a bore 60 a portion of which is internally threaded; and a plurality of spring fingers 61, said fingers being separated by slots 62. For reasons which will be apparent, it is not necessary that the fingers 61 shall be as delicate as the fingers 54; and three or more slots 62 have been found to be sufficient.

Each finger 61 is formed, adjacent its leading end with one or more part-annular sharpened 20 edges 63, the edges 63 of the series of fingers co-operating to form, in effect, annular blades. Within the unthreaded portion of the bore 60 there is reciprocably mounted a plunger 64 formed with a tapered surface 65 adapted to operate with the internal surfaces 66 adjacent the leading ends of the fingers 61. The plunger 64 is preferably provided with a collar 67 of such diameter as to prevent accidental rearward dislodgment of said plunger.

30 It will be seen that the fingers 61 are so arranged as to define an annulus of resiliently variable diameter.

When it is desired to pull a bushing of the character above described, the operator will select a fitting 58 of suitable size, it being obvious that it will be necessary to select a fitting in which the diameters of the circles defined by the edges 63 are, normally, slightly less than the internal diameter of the bushing to be pulled; but 40 in which the diameters of those circles can be sufficiently expanded to drive such edges into the internal surface of the bushing. Applying the selected fitting to the stud portion 34, the operator will insert the fingers 61 into the bushing. 45 Thereafter, holding the fitting 58 against rotation, the operator will rotate the barrel 10 to rotate the stud 33, thereby projecting the stud portion 34 more deeply into the bore 60, and thereby forcing the plunger 64 to move toward the 50 right, as viewed in Fig. 5, to expand the circles defined by the blades 63. Thereby, the blades 63 are positively driven into the material of the bushing.

When the blades have been driven deeply 55 enough into the material of the bushing, the foot-piece 12 is placed in contact with the adjacent surface of the bearing seat, and the stem 23 is rotated in the manner above described to withdraw the fitting 58, and with it the bushing, from 60 the bushing seat.

In Fig. 6, I have illustrated a special fitting particularly designed for the purpose of installing or withdrawing the Ford spring shackle studded bushing. A polygonal fitting 68 is formed with 65 an internally threaded bore 69 for the reception of one end 70 of the shackle and with a threaded extension 71 adapted to be received in the bore 31. The other end 72 of the shackle stud receives a puller fitting 89 which bears against the 70 bushing sleeve end. This fitting is used in the manner above described with respect to the embodiment of Fig. 1.

Fig. 7 illustrates the tool of Fig. 1 modified by the substitution of a plug similar to the plug 24 75 but provided with an enlarged flange 27' formed

to provide one or more radial extensions 73. This plug is used when it is desired to adapt the tool for manipulation of bushings of diameters much larger than those within the normal range of a tool of particular size. To the barrel 10 is applied an auxiliary barrel indicated generally by the reference numeral 74 and preferably, for the purpose of reducing weight, cage-like in construction. Such cage-like auxiliary barrel comprises a top plate 75 and a bottom ring 76 suitably connected by columns 77. Preferably, each column 77 is provided at its opposite ends with reduced threaded extensions (not shown) the lower extensions being threaded into tapped holes in ring 76 and the upper extensions being projected through untapped holes in the plate 75 and secured in place by nuts 78. The upper surface of the top plate 75 is formed with a depression 79 conforming to the flange 27' and projections 73; and the base of said depression is engaged between the flange 27' and the upper end of the barrel 10, whereby the auxiliary barrel 74 is held against axial or rotational movement with respect to the plug 24.

The bottom ring 76 is, in configuration, closely similar to the projecting portions of the footpiece 14; and its bottom surface 80 forms a bearing surface, concentric with the surface 11, and preferably disposed substantially in the plane thereof. With the auxiliary barrel 74 in place, it will be obvious that the tool becomes effectively a bushing puller of very much larger diameter. It will also be obvious that auxiliary barrels of various diameters may be provided, just as I have provided footpieces 12 of various diameters. The 35 limitation upon the diameters of auxiliary barrels to be used in removing the bushings is that the difference between the internal diameter of the bottom ring 76 and the external diameter of the barrel 10 must be at least equal to the thickness 40 of the bushing to be removed; and the limitation upon auxiliary barrels to be used in connection with the seating of bushings is that the external diameter of the bearing surface 80 must be at least slightly greater than the internal diameter 45 of the bushing seat.

With the combination of Fig. 7 I prefer to use a pulling fitting of the character illustrated in Fig. 8, said fitting comprising a ring 81 formed to provide an annular shoulder 82 substantially perpendicular to the direction of movement of the stud 33. Said ring comprises further a cylindrical extension 83; and it is supported on, and may be integral with, a plurality of spokes 84 radiating from a hub 85 which is internally threaded as 55 at 86 for engagement upon the portion 34 of the stud 33. In these large sizes, I prefer to provide a plurality of leaf springs 87 secured to the cylindrical surface 83 to assure a tight-solid fit of the cylindrical portion 83 within the internal 60 surface of the bushing being handled.

I claim as my invention:

1. In a tool of the class described, a barrel having an uninterrupted cylindrical surface and formed to provide an annular foot, a shell fixedly mounted within said barrel and formed with a longitudinal slot therethrough, a sleeve reciprocably mounted within said shell and provided with a lateral projection seated in said slot, a stem journalled in said barrel and normally held 65 against reciprocation with respect thereto, said sleeve and stem being operatively threaded as 70 associated together, a stud removably mounted upon that end of said sleeve adjacent said foot and projectible beyond said foot, and an element 75

threadedly mounted upon the projecting end of said stud and formed to provide a bearing surface facing said foot.

2. In a tool of the class described, a barrel having an annular foot, a stem journalled in said barrel, means providing an annular shoulder non-reciprocable with respect to said stem, an auxiliary barrel abutting said shoulder, means holding the same against rotation with respect to 10 said shoulder, said auxiliary barrel having an annular foot of greater diameter than that of said first-named foot, a stud reciprocably supported in said barrel and projectible therefrom beyond both of said feet, means removably mounted on 15 said stud and providing a bearing surface substantially perpendicular to the direction of movement of said stud, and means providing an operative connection between said stem and said stud to convert rotary movement of said stem with re-

spect to said barrel into linear movement of said stud with respect to said auxiliary barrel.

3. In a tool of the class described, a barrel formed to provide an annular foot at one end, a stem rotatably but non-reciprocably mounted in 5 the closed opposite end of said barrel, a sleeve reciprocably but non-rotatably mounted in said barrel and cooperating with the closed end of said barrel to form a closed chamber, said sleeve being formed to provide an internally threaded 10 socket opening toward said closed end, and said stem being formed to provide a threaded portion operatively received in said socket, whereby rotation of said stem effects reciprocation of said sleeve, and means movable with said sleeve and 15 projectible outwardly beyond said foot for engaging a bushing, or the like.

ROBERT P. KINGSTON.
